INSULATION STRIPPING UNIT

Edward T. Stocker, Groveland, Mass., assignor to Western Electric Company, Incorporated, New York, N.Y., a corporation of New York

Application April 10, 1956, Serial No. 577,238

4 Claims. (Cl. 81—9.51)

This invention relates to an insulation stripping device and particularly to such a device for progressively crushing and stripping insulation from a conductor.

In the manufacture of wire wound resistance elements, as disclosed in the co-pending application Serial No. 578,917, filed April 18, 1956 by G. H. Harmon and A. E. Rockwood, the resistance elements are overwound and then in a resistance calibrating operation, the excess resistance wire of the element is unwound and the insulation is progressively stripped therefrom while the resistance of the remaining wire of the element is continuously compared with a standard. This operation is continued until a predetermined resistance value is reached when the wire is cut at a point which gives the desired final resistance. In order to reduce the time required for this calibrating operation, it is desirable to strip the insulation from the wire at a fast rate at the outset and then reduce the stripping speed when the resistance of the remaining wire approaches the prescribed value.

Accordingly, the main object of this invention is a two-speed insulation stripper particularly suited for use with an impedance calibrator.

In accordance with the general features of the invention, the device utilizes a pair of spring loaded insulation crushing rollers and includes a drive for the rollers which is controlled through a two-speed clutch which permits driving the rollers at either of two speeds.

These and other features of the invention will be more readily understood from the following detailed description taken in conjunction with the accompanying drawings, in which:

Fig. 1 is a top view of the device, partly in section;

Fig. 2 is an isometric view of the crushing roller support mechanism;

Fig. 3 is a side elevational view of the device showing the driving gears for the crushing rollers and the buffers as seen in the plane of line 3—3 of Fig. 1, and

Fig. 4 is a simplified side elevation view, on a reduced scale, showing the exhaust cover for the device.

Referring now to the drawing, in general the insulation stripping device includes a pair of spring biased, opposed, insulation crushing rollers 5 and 6 that strip the insulation from a conductor such as 7 (which may be resistance wire being payed off of an overwound flat type resistor element 8); a buffer wheel 9 and 10 for continually polishing the crushing surfaces of the rollers 5 and 6, respectively; a wire clipper 11; a coaxial clutch 12 for controlling the speed of the rollers 5 and 6; a drive motor 14; an air cylinder 15 for controlling the coaxial clutch 12; and an exhaust cover 13 through which stripped insulation may be removed.

The upper roller 5 on the end of shaft 16 is mounted in the bifurcated housing 17 for limited movement about a pivot pin 18, as controlled by the tensioning of spring 19 on the bolt 20 which threads into the lower housing 22 in which the lower roller 6 is mounted on the end of a shaft 23. The housing 17 will be pivoted slightly upward or clockwise when a wire is passed between rollers

2

and the tensioning of spring 19 thereby applies a crushing pressure therebetween. The amount of displacement of the housing 17 by the wire is not sufficient to break the mesh between gears 25 and 26 which are the power take-off gears for driving the upper roller from the shaft

23. The shaft 23 in turn is driven by the output shaft 38 of the clutch 12. The buffers 9 and 10 are driven by gears 29 and 30 on shafts 16 and 23, through the idler gears 27 and 28 and gears 21 and 24 on shafts 37 and 43 to which the buffer wheels 9 and 10, respectively, are mounted. These buffers keep the surfaces of the rollers clean, thereby preventing jamming between rollers and insuring good electrical contact between the wire being stripped and the rollers which are grounded. In Fig. 1 only portions of the shafts 16 and 37 for roller 5 and buffer 9, respectively, are shown, the gears 21, 27, 25 and 29 having been omitted to permit disclosing shaft 23 (which is driven by the output shaft 38 of the clutch) as well as the gears 26 and 30 on the shaft 23. The vertical disposition of the gearing and shafts for the rollers and buffers is complete in Fig. 3. From this it is seen that gear 26 on the shaft 23 to which roller 6 is attached, is meshed with and drives the gear 25 and its shaft 16 for roller 5.

25 A 1,725 r.p.m. motor 14 drives a jack shaft 32 at 57.5 r.p.m. through a worm gearing 31 having a gear reduction of 30 to 1. The jack shaft in turn drives a "fast" drive clutch member 33 and a "slow" drive clutch member 34 at about 172.5 r.p.m. and 19.2 r.p.m. through 30 a 3 to 1 step-up and reduction arrangement 35 and 36, respectively.

Output shaft 38 of the clutch extends through and is coaxial with and free to slide longitudinally and rotate within the slow drive shaft 39 which is pinned to clutch member 34. A selector member 41 having clutching faces 67 and 68 for engaging faces 69 and 70 of "fast" and "slow" speed clutch members 33 and 34, respectively, is pinned to the output shaft 38 and will rotate at the speed of the clutch face with which it is meshed. The faces of the plates 33, 34 and 41 are notched to provide for a positive gripping therebetween. The "fast" or "slow" speed selection is accomplished by axial movement of the output shaft 38 within the "slow" drive shaft 39, by means of a double-acting air cylinder 15 whose output piston 42 butts with one end of an extension shaft 44 which extends axially from output shaft 38 and is coaxial within the "fast" drive shaft 40. When the piston is advanced the selector 41 meshes with the low or the "slow" speed clutch member 34 and when retracted, 50 a spring 45, mounted against a thrust bearing 46, disengages the selector from the "slow" drive clutch face and meshes it with the "fast" drive clutch face of member 33. This air cylinder 15 is of conventional design and may be controlled by solenoids to advance or retract its piston. 55 This control may be manual or automatic, such as is disclosed in the aforementioned co-pending application. The other end of the output shaft 38 has a slot 47 for receiving a corresponding tongue 48 at the end of shaft 23 for driving the rollers and buffer wheels. This tongue and groove arrangement permits axial movement between the output shaft 38 and the shaft 23 required for operation of the coaxial clutch.

A clipper 11 is provided for clipping the wire in response to a signal (or other manual control) of an 65 electromagnetic device 51 which operates to turn the shaft 52 in housing 22 to which the clipper plate 63 is attached. The clipper plate 63 cooperates with the fixed plate 64 which is provided with an opening 65 through which the wire normally passes. This clipper and plate 64 may be mounted by means of insulating bushings to the housings 22 to electrically isolate the clipper as may be required, for example, in calibrating bare wire resis-

tors. When used in conjunction with the calibrator of the aforementioned application, the solenoid 51 receives its electrical signal from the calibrator.

An exhaust system is provided for continuously removing crushed insulation and wire (which is clipped from the ends of the resistance elements) from the vicinity of the rollers. This comprises an exhaust cover 13 which surrounds the rollers and provides a path to an exhaust outlet 72 connected to a vacuum system.

To insure positive grounding of the rollers when the device is used in conjunction with the calibrator of the aforementioned co-pending application, cantilever springs 73, mounted on the normally grounded cover (shown in dashed lines in Fig. 4 since they are on the inner surface of the cover) may be provided for contacting the rollers.

It is to be understood that the above described arrangements are simply illustrative of the application of the principles of the invention. Numerous other arrangements may be readily devised by those skilled in the art which will embody the principles of the invention and fall within the spirit and scope thereof.

What is claimed is:

1. In an insulation stripping device having a pair of opposing insulation crushing rollers, means for driving said rollers comprising a driver, an output shaft for driving the rollers, a first and a second input shaft, means controlled by the driver for rotating the input shafts at different speeds, a member on each of the input shafts having opposing clutching faces, a member on the output shaft having clutching faces on opposed sides thereof and interposed between the clutching faces of the members on the input shafts, and means for selectively engaging the clutching faces of the output shaft member and the clutching faces of the input shaft members.

2. In an insulation stripping device having a pair of opposing insulation crushing rollers and a drive shaft therefor, means for driving said rollers comprising a driver, an output shaft for driving the drive shaft, coupling means between the output shaft and the drive shaft to permit axial movement therebetween, a first and a second input shaft, means controlled by the driver for driving the input shafts at different speeds, at least one of the input shafts being positioned coaxially with the output shaft, a pair of opposing members on the input shafts with opposing clutching faces, a member on the output

shaft having clutching faces on opposed sides thereof and interposed between the clutching faces of the input shafts, and means for moving the output shaft axially to selectively move one of the clutching faces of the output shaft member into engagement with the clutching faces of the input shaft members.

3. In a device having a drivable member, means for driving the member comprising a driver, an output shaft for driving the member, a first and second input shaft, means controlled by the driver for rotating the input shafts at different speeds, a member on each of the input shafts having opposing clutching faces, a member on the output shaft having clutching faces on opposite sides thereof and interposed between the clutching faces of the members on the input shafts, and means for selectively engaging the clutching faces of the output shaft member and the clutching faces of the input shaft members.

4. In a device having drivable companion members, means for driving the members comprising a driver, an output shaft for driving the members, a first and a second input shaft with at least one shaft having an axial passage extending therethrough for mounting the shaft coaxially with the output shaft, means controlled by the driver for rotating the input shafts at different speeds, a member on each of the input shafts having opposing clutching faces, a member on the output shaft having clutching faces on opposite sides thereof and interposed between the clutching faces of the members on the input shafts, and means for selectively axially displacing the output shaft to engage the clutching faces of the output shaft member and the clutching faces of the input shaft members.
